METHOD OF PRODUCING NITRO-CELLULOSE

Henry Von Kohorn, New York, N. Y.

No Drawing. Application May 22, 1941,
Serial No. 394,619

5 Claims. (Cl. 260—222)

1

My invention relates to an improved nitro-cellulose having a high and stable nitrogen content, and to a method of producing the same.

It also relates to the manufacture of nitro-cellulose or cellulose nitrate with a more stable nitrogen content than known up to now, from cellulose-containing materials which are comparatively poor in cellulose. I can produce by the method hereinafter described a satisfactory nitro-cellulose from raw materials heretofore considered unsuitable for the manufacture of nitro-cellulose.

Up to the present time, nitro-cellulose has been mainly produced from purified cotton or other cellulosic material which was purified to such an extent as to contain almost only pure alpha-cellulose. There exist, of course, a large number of cellulose-containing plants of an alpha-cellulose content of less than 80% and such materials have been considered unsuitable for the manufacture of nitro-cellulose.

Nitro-cellulose was produced by dipping purified cotton or other purified cellulosic matters into a bath containing, for example, 60% sulphuric acid, 23% nitric acid and 17% water. Another suggested nitrating solution contained 2/3 of sulphuric acid and 1/3 nitric acid, the balance being water. The cellulose is left in this bath for a sufficient length of time, for instance one hour, at a temperature which was not allowed to rise freely but which was kept constant.

The use of purified cotton linters or even pure alpha-cellulose prepared from other cellulose-containing materials, such as wood, straw, reeds, or other plants, is of course a costly one due to the purification. Also the nitration of such fibrous matters by the method described above does not result in a very stable nitrogen content of the nitro-cellulose, and many attempts have been made to improve the stability of the said nitrogen content.

I have discovered a method which enables me to use as raw material not only materials containing 100% alpha-cellulose, but also many cellulose-containing materials comparatively poor in alpha-cellulose content. In addition to this, my method results in a nitro-cellulose having a more stable nitrogen content which, if required, may also be higher than produced heretofore.

According to my invention, nitro-cellulose having a high and stable nitrogen content is manufactured by bringing cellulose or cellulose-containing materials into solution by any of the known methods (viscose, cuprammonium, acetate), and then regenerating said cellulose and at the same time nitrating it, by precipitating the solution containing dissolved cellulose in a bath which not only has a precipitating, but at the same time, a nitrating effect on the regenerated cellulose.

2

I shall now describe in detail how I carry out my improved process. When speaking of cellulose herein, I refer to alpha-cellulose.

Example 1

5 Wood pulp with a cellulose content of 83% is dissolved according to the viscose method into viscose containing 16% alpha-cellulose. The said viscose is squirted through a spinneret into a bath containing by weight 2/3 of sulphuric acid and 1/3 of nitric acid, the balance of the bath being water. The threads formed are wound up on a bobbin, which bobbin runs in the same bath. When the bobbin is completely wound, the threads are unwound and boiled in water in order to remove the acid.

10 The threads are then dried and cut into pieces.

Example 2

20 Straw is dissolved according to the cuprammonium method into a cellulose cuprammonium solution containing 12% cellulose. The said solution is forced through a nozzle into a bath containing 60% sulphuric acid, 20% nitric acid and water. The filaments obtained are withdrawn 25 and stored in a tank at the end of the machine containing the same type of bath. When nitration is complete, the said filaments are washed free of acid, dried and cut.

Example 3

30 The cellulose is dissolved into viscose and the said viscose is stored until it is so ripe as to be close to the coagulation point. The viscose is then forced through spinnerets into a bath containing 55% sulphuric acid, 25% nitric acid and 20% water. The fibrous mass obtained is then removed from this first bath and is immediately placed, without intermediate treatment, into a second bath containing 2/3 sulphuric acid, 1/3 nitric acid and the balance consisting of water.

35 After remaining in the second bath for 30 minutes, the fibers are removed, desulphurized by treatment with sodium sulphide solution, washed and dried.

Example 4

40 Wood pulp with a cellulose content of 90% is brought into solution according to the viscose method. The viscose is delivered into a bath containing 2/3 of sulphuric acid, 1/3 of nitric acid, the balance being water. The regenerated cellulose is kept in this bath for 30 minutes at a temperature of 25°C.

Example 5

45 Cellulose is regenerated and nitrated as in Example 4 with the difference that the time during which the cellulose is kept in the bath is 90 minutes.

50 By following any one of the above-described

examples, different types of nitro-cellulose are produced which may have varying contents of nitrogen, but which are extremely stable. It is obvious that by applying a nitrating agent to the cellulose while still in the "status nascendi," the nitrating effect is much stronger and more thorough than when applied to ordinary solid cellulose or cellulose-containing materials.

As another feature of my invention (as described in the examples), I have discovered that my process can be carried out very economically by producing a cellulose solution with a high cellulose content which ordinarily would not be considered suitable for the manufacture of rayon.

In view of the fact that the only purpose of my

process is to produce ordinary solid cellulose having a cellulose content of 50% or more, it is considered that the cellulose solution should not be applied to ordinary cellulose containing more than 50% cellulose.

It is considered that the cellulose solution should not be applied to ordinary cellulose containing more than 50% cellulose.
